Primary Examiner — Mitchell I. Siegel*(74) Attorney, Agent, or Firm* — Finnegan, Henderson, Farabow, Garrett & Dunner, L.L.P.(57) **CLAIM**

The ornamental design of a water ride, as shown and described.

DESCRIPTION

FIG. 1 is a perspective view of a water ride showing my new design;

FIG. 2 a front view thereof;

FIG. 3 a rear view thereof;

FIG. 4 a left side view thereof;

FIG. 5 a right side view thereof;

FIG. 6 is a top view thereof; and,

FIG. 7 is a bottom view thereof.

The portions shown in broken lines in FIGS. 1-7 do not form part of the design. The portions shown in short and long dashes in FIGS. 1, 3, and 6 do not form part of the design and are included solely for the purpose of illustrating the boundary of the design.
